UNITED STATES PATENT OFFICE.

JOHN M. LOCKWOOD, JR., OF JERSEY CITY, NEW JERSEY.

DESIGN FOR A DOLL.

54,427.

Specification for Design. Patented Feb. 10, 1920.

Application filed July 26, 1919. Serial No. 313,636. Term of patent 14 years.

To all whom it may concern:

Be it known that I, JOHN M. LOCKWOOD, Jr., a citizen of the United States, and a resident of Jersey City, in the county of Hudson and State of New Jersey, have invented a certain new, original, and ornamental Design for a Doll, of which the following is a specification.

In the accompanying drawing:

Fig. 2 a side view thereof.

I claim:

The ornamental design for a doll, as shown

JOHN M. LOCKWOOD, JR.

Witnesses:

WILLIAM WARD,
ELIZABETH FRANK.
